[57] CLAIM

The ornamental design for glass rosette for enclosing chandelier sockets and lightbulbs or the like, as shown.

DESCRIPTION

FIG. 1 is a top view of a glass rosette for enclosing chandelier sockets and lightbulbs or the like showing my new design;

FIG. 2 is a side elevation thereof;

FIG. 3 is a side elevation taken along line 3—3 of FIG. 1; and

FIG. 4 is a bottom view.

FIG. 1

FIG. 2

FIG. 3

FIG. 4
